[57] CLAIM

The ornamental design for a cooking tray, substantially as shown and described.

DESCRIPTION

FIG. 1 is a top plan view of a cooking tray, showing our new design;

FIG. 2 is a front elevational view thereof, the rear elevational view being a mirror image thereof;

FIG. 3 is a right side elevational view thereof, the left side elevational view being a mirror image thereof;

FIG. 4 is a bottom plan view thereof;

FIG. 5 is a cross-sectional view thereof, taken on line 5—5 of FIG. 1;

FIG. 6 is a top plan view of a second embodiment of that shown in FIG. 1;

FIG. 7 is a front elevational view thereof, the rear elevational view being a mirror image thereof;

FIG. 8 is a right side elevational view thereof, the left side being a mirror image thereof;

FIG. 9 is a bottom plan view thereof; and

FIG. 10 is a cross-sectional view thereof, taken on line 10—10 of FIG. 6.
